UNITED STATES PATENT OFFICE.

JAMES P. SINCLAIR, OF MOTTVILLE, NEW YORK.

SPOOL OR MANDREL.

SPECIFICATION forming part of Letters Patent No. 537,789, dated April 16, 1895.

Application filed July 28, 1894. Serial No. 518,813. (No model.)

To all whom it may concern:

Be it known that I, JAMES P. SINCLAIR, a citizen of the United States of America, residing at Motvvile, in the county of Onondaga and State of New York, have invented certain new and useful Improvements in Spools or Mandrels, of which the following is a specification.

My invention relates to improvements in spools or mandrels upon which paper or fabrics are wound and the object of the invention is to provide a spool which can be expanded or contracted so that when a roll of paper or fabric is wound on the spool or mandrel it can be contracted and removed from the roll and can then be expanded to its original size.

My invention is illustrated in the accompanying drawings forming part of this specification, in which similar letters of reference indicate corresponding parts in all the figures.

In the drawings Figure 1, is a longitudinal section of the spool when closed or contracted. Fig. 2, is a similar view of the spool two-thirds expanded. Fig. 3, is a perspective view of spool two-thirds expanded partly broken away. Fig. 4, is a cross section of the spool closed, and Fig. 5, is a similar view two-thirds expanded.

30 In the figures C represents the spool or mandrel of any suitable length and approximate diameter, and A represents the shaft or spindle upon which it is mounted.

The shaft is provided with a plurality of 35 slots *a* or depressions milled in its face and preferably arranged in rows. These depressions have inclined bottoms and are designed to receive the inner halves of the balls *o* which rest, when the spindle is contracted, in the 40 deepest portions of said depressions.

A series of strips or staves *i* is provided extending longitudinally of the spindle and these correspond in number to the rows of balls and are provided with corresponding recesses *i'* having inclined bottoms.

In the present drawings I have shown four

staves and four rows of balls but any number might be used, as for instance three, six or more as found necessary or desirable.

The staves are surrounded by a rubber tube 50 D which is slightly smaller in interior diameter than the exterior diameter of the staves when in their contracted position so that the tube will always tend to hold said staves in close proximity to the spindle as shown in 55 Figs. 1 and 4.

The outer end of the spindle is screw threaded and carries a nut B by means of which the spindle may be drawn longitudinally through the cylinder in the direction of the arrow and 60 this will cause the balls to ride upon the inclined bottoms of the depressions and expand the mandrel as shown in Figs. 2, 3 and 5.

I prefer to interpose a washer G between the nut B and the end of the staves to provide a bearing surface for the nut.

The operation of the device in use will be readily apparent, as when in its expanded condition the paper fabric or other material may be wound upon it, and when it is desired 70 to move the mandrel from the roll, the unscrewing of the nut will permit the spindle to move longitudinally and the rubber tube to contract when the spool may be readily withdrawn.

Having thus described my invention, what I claim is—

1. In combination, the spindle, having depressions, balls resting therein the outer expandible cylinder, and means for expanding 80 the cylinder about the spindle, substantially as described.

2. In combination, the spindle having inclined depressions, balls resting therein, the outer expandible cylinder, and means for moving 85 said spindle longitudinally within the cylinder, substantially as described.

3. In combination, the spindle having inclined depressions, the staves having corresponding inclined depressions, balls located 90 in said depressions, an expandible covering for said staves, and means for moving the

spindle longitudinally of the staves, substantially as described.

4. In combination, the spindle having inclined depressions arranged in rows, the staves also having corresponding inclined depressions, the balls located in said depressions, the elastic cylinder inclosing said staves, the nut threaded on the ends of the spindle and the washer interposed between the ends

of the staves and the nut, substantially as described.

In testimony whereof I affix my signature in presence of two witnesses.

JAMES P. SINCLAIR.
